(57) **CLAIM**

The ornamental design of a display screen with graphical user interface, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a display screen with graphical user interface showing our new design.

The broken line showing of a display screen with graphical user interface is included for the purpose of showing portions of the article which form no part of the claim. All text, graph lines and icons shown within the white rectangular box in the graphical user interface form no part of the claimed design.
